VALVE LOADER

Ewing K. Lynn, East McKeesport, Pa., assignor
to The Westinghouse Air Brake Company, Wil-
merding, Pa., a corporation of Pennsylvania

Application September 16, 1936, Serial No. 101,011

6 Claims. (Cl. 303—56)

This invention relates to a valve device in which is provided a slide valve adapted to be reciprocated on a valve seat.

In certain types of valve devices, such as the 5 brake valve device shown in U. S. Patent No. 1,980,334 to Ellis E. Hewitt, a slide valve is employed to control the supply and release of fluid under pressure to and from a fluid pressure operated device, such as the engines for opening 10 and closing the vehicle doors. This slide valve is operated by a cam on the shaft of the brake valve.

The slide valve controls communication between ports in its seat, and as some of these ports 15 are supplied with fluid under pressure, it is necessary to provide means to prevent the slide valve from being lifted from its seat by the fluid acting thereon.

It is desirable also to provide means to yieldingly press the slide valve against the cam on 20 the shaft of the brake valve so that the slide valve will follow the surface of the cam and move to the position determined thereby.

It is an object of this invention to provide 25 means adapted to press a slide valve into engagement with its seat and which will also yieldingly urge the slide valve to move in one direction upon its seat.

A further object of the invention is to provide 30 a valve device having a slide valve movable upon a seat and controlling communication between ports in its seat, a cam for moving said slide valve in one direction upon said seat, and common means for yieldingly pressing the slide valve 35 against its seat and against the face of the said cam.

Another object of the invention is to provide an improved valve device.

Other objects of the invention and features of 40 novelty will be apparent from the following description taken in connection with the accompanying drawing, in which

Fig. 1 is a view, largely in section, of a valve device embodying my invention,

Fig. 2 is a sectional view taken substantially 45 along the line 2—2 of Fig. 1, and

Fig. 3 is a sectional view taken substantially along the line 3—3 of Fig. 2.

Referring to the drawing, the valve device 50 shown therein comprises a casing having a main section 1, a bottom section 2, and a cover section 3, which when secured together form a chamber 5. The bottom section 2 is secured to the main section 1 by means of screws 6, one of 55 which is shown, while the cover section 3 is se-

cured to the main section by means not shown.

The casing section 1 has secured thereto self-lapping valve mechanism, not shown, which may be of the type shown in the above identified patent to Ellis E. Hewitt, and which is operated by 5 a shaft 10 which extends through an opening in the main casing section 1, and has its lower end journaled in a bore in the bottom section 2. The shaft 10 has an operating handle 12 secured thereon by means of which the shaft may be 10 turned to different positions.

The bottom section 2 has a relatively thick portion 13 formed thereon in which is formed a channel having at the bottom thereof a seat, indicated at 14, in which are formed ports 15, 16 15 and 17. The port 15 is supplied with fluid under pressure from a suitable source, such as a supply reservoir, while the port 16 is connected to a door engine, and the port 17 is connected to the atmosphere.

A slide valve 18 is mounted in the channel in 20 the casing section 2 so as to be slidable on the seat 14, and this slide valve has a cavity 20 in the lower face thereof to establish communication between the ports in the seat 14. The slide 25 valve 18 is of such width as to substantially fill the channel in the casing section 2 so as to be guided by the walls of this channel.

One end of the slide valve 18 is reduced in size 30 and projects beyond the thick portion 13 on the casing section 2 and engages one face of a cam follower 22, which has secured thereto guide pins 24 which are slidable in bores in the thick portion 13 of the casing section 2 on opposite sides 35 of the channel in which the slide valve 18 is mounted.

The other face of the cam follower 22 is adapted 40 to be engaged by a cam segment indicated at 26 formed integral with the shaft 10. A portion 45 of the shaft 10 opposite the cam segment 26 is cut away, as is clearly shown in Figs. 1 and 2 of the drawing, and is of such width as to permit the cam follower 22 and the reduced end portion 50 of the slide valve 18 to be moved into this cut away portion of the shaft.

The cover section 3 has a bore therein, indicated at 28, which is substantially in the plane 55 of the channel in the casing section 2. The axis of the bore 28 extends at an angle to the slide 50 valve seat 14, and is arranged to intersect this slide valve seat intermediate the ends thereof. As is clearly shown in Fig. 1 of the drawing, the portion of the bore 28 farthest removed from the cam 26 is farther removed from the plane of the 55

slide valve seat 14 than are the portions of the bore 28 adjacent the cam 26.

A stem 30 is provided and it has an enlarged head 32 having rounded faces thereon slidably positioned in the bore 28. The other end of the stem 30 extends into a socket 33 in the upper face of the slide valve 18, and has a rounded surface which presses against a rounded concave face in a wear resisting insert 34 mounted in the 10 socket 33 in the slide valve 18.

The end of the stem 30 is pressed into engagement with the insert 34 by means of a spring 36 which extends between the cover section 3 and a spring seat 38 secured on the stem 30.

15 The various parts of the apparatus are arranged and proportioned so that when the slide valve 18 is in the position which it assumes when the face of the cam segment 26 engages the cam follower 32, which is a position in which it is shown in Figs. 1 and 2 of the drawing, the socket 33 in the slide valve 18 is located at one side of the axis of the bore 28, while when the slide valve 18 is in the position which it assumes when the face of the cam segment 26 is out of engagement with the cam follower 22, the socket 33 will be located on the other side of the axis of the bore 28.

In operation the spring 26 exerts force through the spring seat 38 to press the end of the stem 30 against the wear resisting insert 34 in the slide valve 18, thereby exerting force on the slide valve to press the slide valve against the seat 14 to prevent unseating of the slide valve by fluid under pressure supplied through the port 15, and at the same time the spring 36 exerts force on the slide valve 18 to move it to the right, as viewed in Figs. 1 and 2 of the drawing, and press against the face of the cam segment 26.

On movement of the operating lever 12 in a 40 direction to move the shaft 10 in a clockwise direction, as viewed in Fig. 2 of the drawing, the cam segment 26 is moved across the face of the cam follower 22, and after a certain amount of turning of the shaft 10, the cam segment 26 will 45 be moved away from the cam follower 22 and will not maintain the slide valve 18 in the position in which it is shown.

On this amount of movement of the shaft 10, the slide valve 18 is moved to the right by force 50 exerted by the spring 36 through the stem 30, while the spring 36 expands somewhat.

The slide valve 18 is moved on its seat from the position in which it is shown, in which the cavity 20 establishes communication between the 55 ports 15 and 16, to a position in which the cavity 20 establishes communication between the ports 16 and 17.

On this movement of the slide valve 18 the head portion 32 of the stem 30 is moved downwardly 60 in the bore 28, while the stem 30 assumes a somewhat different angular position in the bore 28 than that in which it is shown in the drawing. The stem 30 is free to change its position as the rounded head portion 32 permits it to move freely 65 in the bore 28.

On subsequent movement of the operating handle 12 in a direction to turn the shaft 10 in a counterclockwise direction, as viewed in Fig. 2 of the drawing, and thereby return the cam segment 70 26 to the position in which it is shown in Fig. 2 of the drawing, the cam segment 26 presses against the cam follower 22 and moves it to the left, as viewed in Fig. 2 of the drawing, and its movement is transmitted to the slide valve 18 75 to move the slide valve on its seat 14. On this

movement of the slide valve 18, the stem 30 is moved upwardly in the bore 28 in the cover section 3, while the spring 36 is compressed slightly.

It will be seen that the spring 36 operates both to press the slide valve 18 against the seat 14, and to press the slide valve 18 against the face of the cam segment 26 carried by the shaft 10.

The division of the force exerted by the spring 36 on the slide valve 18 to press the slide valve against the seat 14, and to press the slide valve 10 against the cam on the shaft 10 depends upon the angular position of the stem 30. The stem 30 is arranged so that the force exerted on the slide valve 18 to hold it seated is great enough in all positions of the slide valve to prevent the slide valve from being unseated by the fluid under pressure acting thereon. The spring 36 also exerts enough force on the slide valve 18 tending to press it against the cam on the shaft 10 to insure that the valve will move upon its seat when the cam 26 is moved away from the slide valve.

While one embodiment in the improved valve device provided by my invention has been illustrated and described in detail, it should be understood that the invention is not limited to these details of construction, and that numerous changes and modifications may be made without departing from the scope of the following claims.

Having now described my invention, what I 30 claim as new and desire to secure by Letters Patent, is:

1. In a valve device, in combination, a body having a seat thereon having ports therein, a slide valve movable upon said seat to control communication through said ports, a cam associated with said slide valve for moving it in one direction on said seat, and a spring associated with said slide valve for yieldingly pressing said slide valve against said seat and for also pressing said 40 slide valve against said cam.

2. In a valve device, in combination, a body having a seat thereon having ports therein, a slide valve movable upon said seat to control communication through said ports, a cam associated with said slide valve for moving it in one direction on said seat, and a spring associated with said slide valve for yieldingly pressing said slide valve against said seat and for also yieldingly opposing movement of the slide valve by said 50 cam.

3. In a valve device, a body having a seat thereon having ports therein, a slide valve movable upon said seat to control communication through said ports, a cam for moving said slide valve in one direction on said seat, a stem pivotally engaging said slide valve and extending away from said valve seat and away from the slide valve in said one direction, and a spring for pressing said stem against said slide valve 55 whereby said slide valve is yieldingly pressed against said seat and is also yieldingly pressed against said cam.

4. In a valve device, in combination, a body having a seat thereon having ports therein, a slide valve reciprocably movable on said seat in a given plane to control communication through said ports, said body having a bore therein in the plane of movement of the slide valve, said bore extending away from the valve seat in a plane at an angle from the vertical, a stem associated with the slide valve and having an enlarged rounded head slidably in said bore, a spring associated with said stem and pressing said stem 70 75

against said slide valve, and a cam for moving said slide valve against said spring.

5. In a valve device, in combination, a body having a seat thereon having ports therein, a slide valve reciprocably movable on said seat in a given plane to control communication through said ports, said body having a bore therein in the plane of movement of the slide valve, said bore extending away from the valve seat in a 10 plane at an angle from the vertical, a stem associated with the slide valve and having an enlarged rounded head slidable in said bore, a spring associated with said stem and pressing said stem against said slide valve, and means for moving said slide valve against the said spring.

15. In a valve device, in combination, a body having a seat thereon having ports therein, a slide valve reciprocably movable on said seat in

a given plane to control communication through said ports, said body having a bore therein, the axis of said bore being substantially in the plane of the valve seat and intersecting the valve seat intermediate the ends thereof, a slide valve having a socket therein, a stem having an enlarged rounded end thereon slidably mounted in said bore, the other end of the stem extending into the socket in said slide valve, a spring associated with said stem and operating through said stem 10 to yieldingly urge the slide valve to a position in which the socket therein is located on one side of the axis of said bore, and means for moving said slide valve against said spring to a position in which the socket in said slide valve is located 15 on the other side of the axis of said bore.
